UNITED STATES PATENT OFFICE

FRANK HOPPER, OF WHARTON, NEW JERSEY

TYPE BED AND SUPPORT

Application filed December 20, 1928. Serial No. 327,374.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to improvements in a type bed and support.

The principal object of the invention is to provide a support for the safe and rapid handling of containers of explosives while marking them with printed characters.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a plan view of the support;

Fig. 2 is a view in end elevation thereof; and

Figs. 3 and 4 are detailed sectional views on the respective lines of Fig. 1.

In carrying out the invention there is provided a support which consists of a platform or table 5, whose upper surface is covered by a resilient pad 6, preferably of rubber. The pad is confined at each end of the table by means of a rigid plate 7 which projects slightly above the pad for the purpose of better protecting the margin thereof. The extremities of the plates also extend beyond the sides of the table and in each of such extended portions 8 there is firmly secured a block 9 formed with an aperture 10 disposed parallel with the sides of the table.

A rod 11 is mounted in the apertures of each pair of opposite blocks and conveniently secured by means of set screws 12. The spaced rods serve to carry any required number of type holders 13 of similar construction. Each of the holders consists of a bar, U-shaped in cross section, and having fixed at each end a pair of spaced blocks 14 between which is received the tongue 15 of a carrier 16, slidably mounted on the rod. The carrier may

be held in fixed position by means of a set screw 17. The type 18 which is placed in the holder and resiliently held thereby is of a commercial design.

Before commencing the operation of stamping, the type holders are adjusted to a position determined by the arrangement of the markings for the particular class of articles to be stamped. In placing the article on the table, one edge may abut against the end plate 55 7 which serves as a distance gage with respect to the type holders and the article is then lowered on to the type holders, pressure being exerted to insure the impress of a clear and legible marking. By a practical continuous 60 65 rolling operation the article is advanced across the table and removed.

I claim:

1. A printing table embodying a support, a resilient work-supporting covering thereon, rigid end plates on the support confining the covering and projecting above the same, rods mounted on the opposed extremities of the end plates, carriers slidable on the rods and having tongues directed towards the support, a U-shaped bar disposed transversely of the table and spaced blocks in each extremity of the bar receiving the tongue of a carrier. 70 75

2. A printing table embodying a support, a resilient work-supporting covering thereon, rigid end plates on the support confining the covering, rods mounted on the opposed extremities of the end plates, carriers slidable on the rods and having tongues directed towards the support, a U-shaped bar disposed transversely of the table and spaced blocks in each extremity of the bar receiving the tongue of a carrier. 80 85

3. A printing table embodying a support, a resilient work-supporting covering thereon, rigid end plates on the support confining the covering, rods mounted on the opposed extremities of the end plates, carriers slidable on the rods and a type holder retained by opposite carriers. 90 95

FRANK HOPPER.
